HOLDER FOR COSMETICS

Henry Groh, Glen Spey, N. Y., assignor of one-half to Harry W. Cron, Port Jervis, N. Y.

Application September 21, 1948, Serial No. 50,300

1 Claim. (Cl. 206—56)

1

This invention relates to holders for such cosmetics as lipsticks, cheek sticks and the like.

It has for an object to provide a lipstick holder which is simple to manufacture, employs few working parts and is formed from a minimum amount of metal.

A further object of the invention is to provide a new and useful holder for lipsticks and the like which is constructed in a simple manner and thus avoids jamming or like disadvantages in use.

Generally, in practicing the present invention, there is provided a holder for lipstick or kindred goods having a single shell base with a slot therein, the lipstick being carried in a conventional cup within the shell and being raised or lowered by an elevation arranged outside the shell and connected to the cup through the slot, the connection between elevator and cup being such that a frictional gripping of the shell will be maintained until the elevator is pressed inwardly when the frictional grip will be relieved to permit raising and lowering of the lipstick. Thus, the lipstick will be frictionally held at any position it is elevated to. A suitable cap is provided of conventional form, if desired, whereby a simple, economical but sturdy complete lipstick holder or case is attained using a minimum of metal for the parts and simple practically fool-proof elevating means.

Reference will now be made to the accompanying drawings illustrating the invention.

In the drawings:

Figure 1 is a cross-sectional elevation of a holder according to the invention on a somewhat elongated scale, but without any cap being shown;

Figure 2 is a plan view of the holder of Fig. 1 but with the lipstick removed therefrom for clarity;

Figure 3 is a breakdown view of the component parts of the holder of Fig. 1;

Figure 4 is an elevation of a modification of the holder of the present invention, with parts shown in section;

Figure 5 is a side elevation of a holder according to the invention shown closed with a cap in position;

Figure 6 is a front elevation of the holder of Fig. 5; and

Figure 7 is an elevation of another modification of the present invention using two holders with a common enclosure member.

Referring to the drawings, in Figs. 1, 2 and 3 there is shown the holder for lipstick or the like

2

without a cap thereon. An outer tubular shell 10 formed preferably of a single piece of metal and having one end closed is provided in its wall with a longitudinal slot 11. A cup 12 for holding a lipstick or like cosmetic stick 13 (Fig. 1) has a diameter such that it can fit within the interior of shell 10.

Cup 12 is elevated and lowered within shell 10, in order to raise the lipstick for use and thereafter lower same for safe storage, by means of an elevator 14 formed as a long narrow bar of metal or plastic material, and fastened to said cup through slot 11. In accordance with one feature of the present invention this fastening is in the form of a metal member 15 having at least one section which is resilient in the form of a U-shaped spring 16 one leaf of which is attached to elevator 14, as at 17. At the extremity of member 15 there is a small upturned portion 18 which is adapted to enter a cut-out 19 in the base of cup 12 to permit the fastening of the cup to elevator 14. The fastening comprising portions 15, 16, and 18 may be formed in one piece if desired, for instance, of metal, or it may be formed of separate pieces attached together and made of any material serving the purpose described. In order to assemble the holder parts together, the elevator 14 with member 15 attached is placed in position on shell 10 with the elevator outside the shell and the member 15 protruding through slot 11 into the interior of the shell. The cup 12 can now be quickly fastened in position by inserting portion 18 into cut-out 19 and crimping the metal of portion 18 over. Because of the U-shaped spring 16, cup 12 will be in resilient frictional contact normally on one side with the interior wall of shell 10, this contact being at the side where slot 11 appears, and upon pressure of the fingers or thumb on elevator 14 or movement thereof, the frictional contact will be relieved to permit free raising or lowering of the lipstick 13 within shell 10. However, upon release of pressure on elevator 14, the frictional contact will be again existent so that any position of the lipstick can be preserved without danger of the lipstick falling back into the shell or being pushed back by pressure exerted in use. The dimensions of slot 11 and of elevator 14 are so related that slot 11 is completely covered by elevator 14, thus keeping the slot isolated from dust or other contaminating particles which would be picked up by the lipstick. Any suitable cap or cover may be applied to the holder illustrated in Figs. 1, 2 and 3.

In Fig. 4 there is shown another form of holder

according to the present invention which particularly could be used for stick base make-up, shaving sticks or like products.

A casing 20 is provided with a lid 21 hinged at 22. A cup 23 carries the stick 24.

An elevator 25 accommodated in a slot 29 in the body of casing 20 is attached to cup 23 by a U-shaped spring 26, a leg of the spring being attached, for example by soldering, to the inside face of elevator 25 and the outside wall of cup 23, respectively.

Thus again, by pressing inwardly on elevator 25 the frictional contact, normally maintained between the cup on one side near the slot and the inside face of the casing, will be relieved and, upon removal of such pressure, the frictional engagement will hold the cup in the position thus set.

Figs. 5 and 6 are two views of a holder similar to the holder of Figs. 1, 2 and 3 but with a special cap in position. Upon shell 16 there is affixed a cap member 30 with a sliding fit on the outer surface of the shell. In order to accommodate the elevator 14 and at the same time cause an amount of locking thereof against displacement, for instance in a woman's handbag, cap 30 is cut away to form a long slot 31 which is contoured to embrace the side faces 32 and one end face 33 of elevator 14.

The fit of slot 31 about elevator 14 is a smooth sliding contact of the adjacent contact surfaces, whereby raising of the elevator 14 with cap 30 in position is rendered difficult and thus accidental displacement of the elevator is inhibited. If the thickness of the elevator 14, namely, the height of sides 32, is the same as the thickness of metal forming cap 30, a further feature of the invention is accomplished, as clearly shown in Fig. 5, of presenting a smooth continuous surface of cap 30 and shell 16, with no upjutting pieces to catch lint or the like, for instance in a handbag or like receptacle. However, the elevator 14 may be formed of greater thickness and may be also serrated or otherwise patterned on the front face 34 (Fig. 6) for improving the grip of a finger or thumb thereon.

In Fig. 7 there is illustrated a further modification of the invention in which two holders according to Figs. 1, 2 and 3 are united with a common closure means. A pair of shells 10 are assembled as shown in Fig. 1 with their elevators 14 and cups for containing sticks of cosmetics or the like. A hollow tube 35 is slidably engaged with each shell 10 on its outer surface to form a common closure to the two holders which may

contain different shades of lipstick, for instance, or different types of cosmetics. Obviously, tube 35 may be provided with slots at each end similar to slot 31 of Figs. 5 and 6, if it is desired to ensure greater safety from accidental elevating of either elevator 14.

I claim:

A holder for a lipstick or the like, comprising a cylindrical base shell closed at one end thereof, a vertical slot in the wall of the shell, the slot extending from adjacent the lower end of the shell to a point above the transverse medial line, a cup for supporting a lipstick in a vertically upright position and disposed for vertical movement within the shell, the cup having a diameter slightly less than the internal diameter of the shell, the cup having a closed bottom, the bottom having an opening disposed therein at a point diametrically opposite to the slot, means for resiliently and releasably holding the cup against the inside of the shell adjacent the slot comprising a U-shaped flat spring having legs of unequal length, the longer leg having a supporting arm at right angles thereto engaging the bottom of the cup and supporting the same, the free end of the supporting arm having an upturned portion at right angles thereto, the upturned portion extending through the opening in the bottom of the cup and fastened to the cup, the short leg of the U-shaped flat spring extending through the vertical slot of the shell, an elevator attached to the short leg, the elevator being longer and wider than the vertical slot so as to entirely cover the same when the cup is withdrawn into the shell, the U-shaped 40 spring normally urging the cup against the inside wall of the shell adjacent the vertical slot so as to frictionally engage the same and upon inward and upward pressure on the elevator the frictional pressure is relieved and the cup may be elevated and lowered.
